UNITED STATES PATENT OFFICE.

ABRAHAM GRANT WEISER, OF SOUTH PASADENA, CALIFORNIA.

DOOR AND LATCH HANDLE.

1,095,611.

Specification of Letters Patent.

Patented May 5, 1914.

Application filed April 11, 1913. Serial No. 760,354.

To all whom it may concern:

Be it known that I, ABRAHAM GRANT WEISER, a citizen of the United States, residing at South Pasadena, in the county of 5 Los Angeles, State of California, have invented new and useful Improvements in Door and Latch Handles, of which the following is a specification.

This invention relates to a combined door 10 and latch handle for doors and night latch locks such as I have shown in my design Patent No. 43,561 issued February 11, 1913; and the invention consists particularly in a 15 construction embodying a concealed latch handle and lever set within the door handle in an open topped slot at the top of the handle, a button or other projection extending above the handle for engagement by the thumb to operate the latch of the lock.

20 My invention may take various forms; and I will explain typical constructions in the following specification, reference being had to the accompanying drawings, in which:

25 Figure 1 is a vertical section showing one form of my improved combination handle applied to a door and lock. Fig. 2 is a plan showing the combination handle illustrated in Fig. 1. Fig. 3 is a fragmentary section 30 showing a variation of the form shown in Fig. 1.

Referring to the drawings, 10 may designate a door and 11 any type of mortise lock therein, the lock having a latch operating 35 arm or member 12 with which the inner end 13^a of the latch lever 13 is adapted to engage. A plate 14 may be of any desired design to carry the handle 15. The handle 15 may be of any configuration; its essential 40 feature being the inclusion of a cavity or opening 16 in its upper part in which the latch lever 13 is housed. The latch lever 13 is concealed within the upper part of the handle 15, and only a button 17, or any 45 other suitable projection, as is illustrated in Fig. 3 at 17^c projects above the upper part of handle 15.

In Fig. 1 I have shown the lever 13 as 50 being pivoted on a pivot lug 18, being guided laterally by fitting more or less closely in the slot 16. The shoulders 31 limit the upward movement of the lever. The upper edge of the lever 13 comes practically flush with the upper surface of the handle 55 15; and the general appearance of the device is that of a plain handle with a button

or other member projecting above in a convenient position for operation by the thumb when the handle 15 is clasped in the hand.

In Fig. 3 I have shown a form somewhat 60 similar to that shown in Fig. 1, but herein I have shown a projection 17^c on the lever 13^c to take the place of the button 17. The operation of the device is not affected by this change; the slot 16^c in handle 15^c being the 65 same as before explained, and the shoulder 31^c acting to stop the latch movement.

It will be seen that the broad feature of my invention is the combination of a door handle and latch lever, with the latch lever 70 set in a slot in the upper part of the door handle and concealed thereby, a button or other engageable member projecting above the handle to be operated by the thumb.

The invention involves great mechanical 75 conveniences both in construction and in operation. The door handle itself forms a convenient support for the pivot of the latch handle; and the latch handle is in the most 80 convenient position for efficient operation. Moreover, my device presents an extremely 85 slightly appearance.

Having described a preferred form of my invention, I claim:

1. In combination, a relatively immovable 85 door handle having a slot in its upper part open at the upper surface of the door handle, a pivot lug at the bottom of the slot, a relatively movable latch lever concealed within said slot and having its upper 90 surface normally flush with the upper surface of the handle, and a manually engageable button integral with the lever and projecting above the door handle, said lever having a depression in its bottom surface engaging 95 over the pivot lug to pivotally support the lever.

2. In combination, a plate and a relatively immovable door handle mounted thereon, the handle having a slot in its upper 100 part open at the upper surface of the handle and the plate having an aperture registering with the handle slot, a pivot lug at the bottom of the slot near the plate, a latch lever lying in the slot with its upper 105 surface normally flush with the upper surface of the handle, the lever having a depression in its bottom surface engaging over the pivot lug and the lever projecting through the plate opening with its upper 110 surface close to the upper edge of the opening, a rearwardly facing shoulder on the

upper side of the lever adapted to engage the front face of the plate when the lever is in its normal position, and a manually engageable button on the forward end of the lever 5 projecting above the upper surface of the handle.

In witness that I claim the foregoing I

have hereunto subscribed my name this 4th day of April 1913.

A. GRANT WEISER.
